CLAIM

The ornamental design for a motorcycle tire, as shown and described.

DESCRIPTION

FIG. 1 is a front view of a motorcycle tire showing my new design, it being understood that the tread design is repeated uniformly throughout the circumference of the tire and the opposite side is the same as that shown;

FIG. 2 is a right side view thereof;

FIG. 3 is a top plan view thereof; and,

FIG. 4 is a left side view thereof.
